US0D1033580S

(12) **United States Design Patent** (10) Patent No.: **US D1,033,580 S**
(45) Date of Patent: ** Jul. 2, 2024

(54) **GOLF CLUB HEAD**

(71) Applicant: **PARSONS XTREME GOLF, LLC**,
Scottsdale, AZ (US)

(72) Inventors: **Matthew T. Andrews**, Scottsdale, AZ
(US); **Robert R. Parsons**, Scottsdale,
AZ (US)

(73) Assignee: **PARSONS XTREME GOLF, LLC**,
Scottsdale, AZ (US)

(**) Term: **15 Years**

(21) Appl. No.: **29/907,987**

(22) Filed: **Jan. 10, 2024**

Related U.S. Application Data

(63) Continuation-in-part of application No. 29/921,968,
filed on Dec. 20, 2023, which is a continuation-in-part
of application No. 29/905,435, filed on Oct. 20, 2023.

(51) **LOC (14) Cl.** **21-02**

(52) **U.S. Cl.**

USPC **D21/759**
